UNITED STATES PATENT OFFICE

2,575,154

ROTARY PUMP

Carl Michael Zoll, New Orleans, La., assignor to
Hydro Power, Inc., New Orleans, La., a corpora-
tion of Louisiana

Substituted for abandoned application Serial No.
600,305, June 19, 1945. This application De-
cember 18, 1950, Serial No. 201,503

2 Claims. (Cl. 103—4)

1

This invention relates to rotary pumps and has special reference to a multiple rotary pump. This application is a substitute for abandoned application No. 600,305 filed June 19, 1945.

One important object of the invention is to provide a novel and compact arrangement wherein a number of rotary pumps are arranged in a circle in a housing common to all said pumps.

The second important object of the invention is to provide a novel arrangement of multiple rotary pump having a common supply to all of the pump cylinders and a common outlet from all of said pump cylinders.

The third important object of the invention is to provide a novel device of this kind which may be driven from a motor and either directly connected to the housing of the motor or to a reduction gear housing driven in turn by the motor.

With the above and other objects in view the invention consists in general of certain novel details of the construction and combinations of parts hereinafter fully described, illustrated in the accompanying drawings, and particularly claimed.

In the accompanying drawings, like characters of reference indicate like parts in the several views and:

Fig. 1 is a side elevation of the invention.

Fig. 2 is a detail section on the line 2—2 of Fig. 3, the view being partly diagrammatic.

Fig. 3 is a section taken substantially on the line 3—3 of Fig. 2 but extending through the entire device.

Fig. 4 is a section on the line 4—4 of Fig. 3.

In the embodiment of the invention herein disclosed there is provided a housing 10 having a circular body portion 11 wherein are formed the pump cylinders 12 of the ordinary shape. These pump cylinders are arranged in equidistances around the center of the circular body 11 and are equally spaced around the lower part thereof. Leading outwardly from each of the pump cylinders are intake ports and surrounding the various intake ports is a manifold 14 having a supply inlet 15 provided with a suitable flange 16 by means of which it may be connected to any source of supply. Centrally of the body 11 is an outlet passage 17 extending through a boss 18 which may be used for connection of an outlet pipe to carry the fluid from the pumps to any desired place. Ports 19 radiate from this outlet 17 to the various cylinders 12, these ports being curved to render outflow easy.

In each of the cylinders there is provided a pair of pump elements 20 of the usual interlock-

2

ing form so that when these pump elements are revolved they force the fluid being pumped through the cylinders. The pump cylinders open to the rear of the body 11 so that these elements 20 may be inserted therein but a closure 21 is fitted in a circular recess 22 and engages on a gasket 23 which seals the inner ends of the pump cylinders. Each pump element is provided with a shaft 24 which extends through the member 21 into a hollow circular housing 25. While no means has been shown in the present drawings it is to be understood that any suitable packing may be used in connection with the shaft 24 to prevent any leakage at this point. Such packings are, however, well known, and it is not deemed necessary here to describe the same. Keyed or otherwise secured to the shafts 24 are gears 26 which mesh with each other and consequently causes the elements 20 to revolve in unison. It will be observed from Fig. 2 that there are a number of groups of gearings and that in each group one of the shafts 24 has keyed or otherwise secured thereto a gear 27 which meshes with a gear 28 fixed on a centrally disposed shaft 29 which extends through housing and through a flange member 30 which may be welded or otherwise secured to the housing 23 for the purpose of supporting entire device. Obviously other means of support may be used but this has been here illustrated as one convenient manner of supporting directly on either a slowly rotating motor or on a reduction gear housing driven by a motor.

In operation the fluid enters through the passage 15 and is distributed by the manifold 14 to the various ports 13 from which the pumps drive it through to the central discharge openings 17.

While only five pump cylinders have been here shown it is obvious that any desired number may be used, the entire matter depending on the diameter of the body 11 and the size of the cylinders.

What is claimed is:

1. In rotary pumping mechanism, a housing having a body portion and having a series of pump chambers spaced concentrically about the axis of said body portion, an intake port at the bottom of said housing, a pair of arcuate passages within said housing, said passages extending in opposite directions from said intake port, said passages tapering from the said intake port in cross section whereby to obtain uniform suction in the pump chambers, said passages having port communication with said pump chambers, said housing having an outlet axially positioned with reference to said body portion, said housing

having passages extending radially of said body portion from the pump chambers to said outlet, pumping elements in said chambers, and means to drive said pumping elements.

2. In rotary pumping mechanism, a housing having a body portion and having a series of pump chambers spaced concentrically about the axis of said body portion, an intake port at the bottom of said housing, a pair of arcuate passages within said housing, said passages extending in opposite directions from said intake port, said passages tapering from the said intake port in cross section whereby to obtain uniform suction in the pump chambers, said passages having port communication with said pump chambers, said housing having an outlet axially positioned with reference to said body portion, said housing having passages extending radially of said body portion from the pump chambers to said outlet, said radial passages having their inner ends curved in the direction of flow from said outlet where-

by to avoid turbulence in the outlet, pumping elements in said chambers, and means to drive said pumping elements.
